(57) **CLAIM**

The ornamental design for a split groin undergarment, as shown and described.

DESCRIPTION

FIG. 1 is an isometric view of a split groin undergarment in the closed configuration;

FIG. 2 is front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an isometric view of a split groin undergarment in the open configuration;

FIG. 9 is front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

Dash-dot-dash lines in the figure drawings represent unclaimed boundaries only and form no part of the claimed design. Evenly broken lines in the figure drawings represent unclaimed environment only and form no part of the claimed design. Broken lines with perpendicular elements represent stitching and form no part of the claimed design.

1 Claim, 14 Drawing Sheets
